U.S. Cl. D7—16

FIG. 1

FIG. 2

FIG. 3

FIG. 4

FIG. 5

FIG. 1 is a top plan view of a crisper showing my new design;

FIG. 2 is a side elevational view thereof;

FIG. 3 is a bottom plan view thereof;

FIG. 4 is an end elevational view thereof;

FIG. 5 is a partial cross-sectional view on an enlarged scale taken along line 5—5 of FIG. 3.

The crisper as is particularly depicted in FIGS. 3 and 5 includes as a characteristic feature thereof inwardly protruding integral bottom wall ribbing of triangular configuration.

I claim:

The ornamental design for a crisper, substantially as shown and described.
